UNITED STATES PATENT OFFICE.

FRIEDRICH C. BAST AND EMIL J. BAST, OF GARY, MINNESOTA.

GEARING.

1,092,328.

Specification of Letters Patent.

Patented Apr. 7, 1914.

Application filed May 17, 1913. Serial No. 768,202.

To all whom it may concern:

Be it known that we, FRIEDRICH C. BAST and EMIL J. BAST, citizens of the United States, residing at Gary, in the county of 5 Norman and State of Minnesota, have invented certain new and useful Improvements in Gearing; and we do hereby declare the following to be a full, clear, and exact description of the invention, such as will enable others skilled in the art to which it 10 appertains to make and use the same.

Our invention has for its object to provide an improved dust proof gear casing intended for general use but especially designed to be used in connection with steam and gasoline traction engines, for covering the driving gears and meshing pinions of their traction wheels.

To the above ends, generally stated, the 20 invention consists of the novel devices and combinations of devices hereinafter described and defined in the claims.

In the accompanying drawings, which illustrate the invention, like characters indicate like parts throughout the several views.

Referring to the drawings: Figure 1 is a view partly in longitudinal vertical section and partly in plan, showing our invention applied to a traction engine; Fig. 2 is a view principally in side elevation of the parts shown in Fig. 1, some parts being sectioned on the line $x^2 x^2$ of Fig. 1 and some parts being broken away; Fig. 3 is a detail view 35 in longitudinal vertical section, taken on the line $x^3 x^3$ of Fig. 1; and Fig. 4 is a detail view partly in side elevation and partly in horizontal vertical section, taken on the line $x^4 x^4$ of Fig. 1.

For the purpose of showing our invention in working position, a portion of a traction engine has been illustrated in the drawings. Of the parts of the said engine, the numeral 1 indicates one of its traction wheels loosely 45 journaled on a rear axle 2 mounted in a bearing 3 on the frame 4. Mounted on the inner end of the hub of the traction wheel 1 and rigidly secured to rotate therewith is a large driving gear 5, with which meshes a 50 cooperating pinion 6, keyed to a counter shaft 7, journaled in a bearing 8 on the frame 4. The parts thus far described may be of the standard or any desired make.

Referring now to our invention, the numeral 9 indicates a pair of reversely extend-

ed joint flanges secured, by means of angle brackets 10, to the opposite sides of the rim of the gear 5. Mounted on the joint flanges 9 and completely spanning the distance therebetween, to cover the peripheral portion of the gear 5, is a sheet metal annular casing 11, channel-shaped in cross section. The longitudinal edges of the casing 11 are bent laterally outward, to afford annular joint flanges 12, to the inner faces of which 60 are secured, by rivets, annular wearing strips 13 within which the joint flanges 9 rotate in close engagement. Brackets 14 rigidly connect the casing 11 to the frame 1. In the drawings, only two brackets 14 are 65 shown, but, of course, any number may be provided to securely hold the casing in its proper position. At its upper portion, the casing 11 is transversely divided and the ends thereof are overlapped at 15, to afford 70 a dust proof joint. As best shown in Figs. 2 and 3, the overlapped ends of the joint flanges 12 and wearing strips 13 are reversely beveled and overlapped, to form a 75 loose splice.

For circumferentially expanding and contracting the joint flanges 12 on the joint flanges 9, a pair of screw rods 16 is provided. These screw rods have threaded engagement, at their ends, with nut lugs 17 secured on the 80 joint flanges 12 and are provided, at their intermediate portions, with a squared section 18, to which an operating wrench may be applied, for rotating the same.

To clamp the overlapped ends 15 of the 85 casing together, to afford a dust proof joint, a nut equipped bolt 19 is passed through coincident elongated slots 20, formed in the transverse portions of said overlapped ends. Obviously, these elongated slots 20 permit 90 circumferential expansion and contraction of the casing 11.

The transverse portion of the casing 11 is cut away at 21, to receive the pinion 6, and the same is transversely divided at 22, to 100 permit the improved casing to be assembled around the pinion 6, and the adjacent portions of the joint flanges 12 are overlapped and detachably connected by means of nut equipped bolts 23. A removable hood 24 is 105 provided for covering the exposed portions of the pinion 6 and for closing the opening 21, thus affording a dust proof covering for said pinion. The hood 24 is provided with laterally projecting flanges 25 detachably 110

secured to the casing 11 by nut equipped bolts 26. The sides of the hood 24 overlap the adjacent sides of the casing 11, and the sides of said hood and casing are provided with reversely formed segmental notches 27 that embrace the counter shaft 7. In actual usage, suitable packing may be interposed between the overlapped ends 15 of the casing 11 and between the hood 24 and the adjacent portions of the casing 11.

10 Oil Z, in which the lower portion of the gear 5 runs, is introduced into the casing 11 through an opening 28 formed in the transverse portion of the casing 11, adjacent to one of its overlapped ends 15. This opening 28 is normally closed by a swinging cover 29, pivotally secured, at one end, to the casing 11 by a pivot pin 30 and having, at its free end, a detent 31 adapted for interlocking engagement with an aperture 32 formed in the casing 11. Grease cups 33 are secured to the joint flanges 12, for introducing oil between the wearing strips 13 and the joint flanges 9. A discharge nipple 34 is provided at the bottom of the casing 11, for drawing off the old oil within said casing. This nipple 34 is normally closed by a screw cap 35.

From the above description, it is evident 30 that the improved casing will exclude all dirt and dust from the gear 5 and co-operating pinion 6. By means of the rods 16, the joint flanges 12 may be circumferentially adjusted, so as to closely fit the joint 35 flanges 9 to form dust proof joints therebetween. The oil from the grease cups 32 will keep the joint flanges 9 and wearing strips 13 sufficiently well oiled to cause the joint flanges 9 to freely rotate with the 40 wearing strips 13. Obviously, new wearing strips 13 may be provided from time to time to replace the old ones, and the screw rods 16 may be adjusted to take up the wear between the joint flange 9 and the 45 wearing strip 13 and thereby maintain the proper joint between the parts. Sufficient oil may be placed in the casing 11, through the opening 28, to cause the lower part of the gear 5 to run therein. The teeth of the 50 gear 5 will carry sufficient oil to keep the pinion 6 well lubricated. The hood 24 may be moved from time to time, to permit inspection of the pinion 6 and adjacent portion of the gear 5.

55 What we claim is:

1. The combination with a gear having reversely extended joint flanges, of an annular casing having joint flanges seated on the joint flanges of said gear, and means 60 for expanding and contracting the joint flanges of one of said members, substantially as described.

2. The combination with a gear having reversely extended annular joint flanges, of 65 an annular casing having joint flanges

seated on the joint flanges of said gear, said casing being transversely divided and the ends thereof overlapped, and an adjusting device connecting the ends of said casing for expanding and contracting its joint flanges on the joint flanges of said gear, substantially as described.

3. The combination with a gear having reversely extended annular joint flanges, of 70 an annular casing having joint flanges seated on the joint flanges of said gear, means securing said casing against rotation, means for expanding and contracting the joint flanges of said casing on the joint flanges of said gear, substantially as described.

4. The combination with a gear having reversely extended annular joint flanges, of 75 an annular casing having joint flanges seated on the joint flanges of said gear, said casing being transversely divided and the ends thereof overlapped, adjusting devices connecting the ends of said casing for expanding and contracting its joint flanges on the joint flanges of said gear, substantially as described.

5. The combination with a gear and a pinion meshing therewith, of reversely extended annular joint flanges on its rim, of 80 an annular casing having joint flanges seated on the joint flanges of said gear, said casing being transversely divided and the ends thereof overlapped, screw threaded adjusting rods for expanding and contracting the joint flanges of said casing on the joint flanges of said gear, means securing said 85 casing against rotation, said casing having an opening through which said pinion may be inspected, and a removable cover for the opening in said casing, substantially as described.

6. The combination with a gear and a pinion meshing therewith, of reversely extended joint flanges secured to the rim of 90 said gear, an annular casing having joint flanges seated on the joint flanges of said gear, said casing being transversely divided and the ends thereof overlapped, reversely screw threaded rods for expanding and contracting the joint flanges of said gear, means 95 securing said casing against rotation, said casing having an opening through which said pinion projects, a removable hood secured to said casing and covering said pinion, and a nut equipped clamping bolt mounted in elongated coincident slots 100 formed in the overlapping ends of said casing, substantially as described.

7. The combination with a gear and a pinion meshing therewith, of reversely extended joint flanges secured to the rim of 105 said gear, an annular casing having joint flanges seated on the joint flanges of said gear, said casing being transversely divided and the ends thereof overlapped, reversely screw threaded rods for expanding and 110 contracting the joint flanges of said gear, substantially as described.

tracting the joint flanges of said gear, means
securing said casing against rotation, said
casing having an opening through which
said pinion projects, a removable hood se-
5 cured to said casing and covering said pin-
ion, a nut equipped clamping bolt mounted
in elongated coincident slots formed in the
overlapping ends of said casing, a normally
closed oil opening at the top of said casing,
10 and a normally closed discharge nipple at

the bottom of said casing, substantially as
described.

In testimony whereof we affix our signa-
tures in presence of two witnesses.
